UNITED STATES PATENT OFFICE.

KIMBALL V. CLARK, OF BUFFALO, NEW YORK.

SPRING-HINGE.

No. 800,074.

Specification of Letters Patent.

Patented Sept. 19, 1905.

Application filed July 15, 1904. Serial No. 216,709.

To all whom it may concern:

Be it known that I, KIMBALL V. CLARK, a citizen of the United States, residing at Buffalo, in the county of Erie and State of New York, have invented new and useful Improvements in Spring-Hinges, of which the following is a specification.

This invention relates to spring-hinges of that class in which the spring is mounted in a frame independent of the leaves of the hinge, the frame being so connected with the leaves that the force of the spring throws the leaves in either direction with equal facility or maintains the said leaves in proper resilient relation.

The spring-frame particularly embodying the features of the invention is readily detachable from or applicable to the leaves by imparting thereto a rolling motion in either one of two directions in contradistinction to a direct pull or inward push with respect to the leaves to facilitate detachment or assemblage of a screen-door or other movable closure with which the hinge may be used without requiring the removal of the fastening devices of either hinge-leaf. The spring is wholly carried by the frame therefor, and said frame is composed of two interacting or movable members with which the spring-terminals individually engage, the heads or ends of the members having stops in reverse positions engaging a part of each frame member and operating to limit or restrict the resilient action of the spring to avoid too great inner contraction of the members to permit the application and separation of the spring-carrying frame and spring with respect to the hinge-leaves, but at the same time set up sufficient tension on the members of the frame to insure a locking assemblage thereof of sufficient resistance to counteract any tendency to accidental displacement. The members of the spring-carrying frame have inner projections or tongues to engage openings or slots at intermediate points in the leaves of the hinge, said projections or tongues being normally a less distance apart than the nearest walls of the openings or slots, the opposite ends or extremities of the spring-carrying frame when applied to the hinge-leaves being loosely disposed close to the hinge-knuckles and unconnected to the latter.

In springs of this class as heretofore usually constructed projecting ears have been employed for releasing the spring and require

extreme manual force to overcome the resistance of the spring, both in the setting and detaching operations, the said ears not only adding to the expense of manufacture, but always liable to breakage, and when broken the hinge becomes practically useless as a detachable organization, and under the most favorable circumstances the parts can only be separated by the introduction of some tool between the leaves and the spring-frame. This disadvantage is overcome by the present form of hinge, and particularly in view of the terminal stops carried by the members of the spring-frame and which arrest the tension of the spring exactly at the desired point and separate the projections, tongues, or claws sufficiently to form entering wedges in relation to the slots or openings in the leaves, and by this construction also the hinge is rendered more strong and durable and the operations of detaching and assembling the parts of the hinge are simplified.

In the drawings, Figure 1 is a front elevation of a hinge embodying the features of the invention. Fig. 2 is a similar view of the hinge-leaves. Fig. 2^a is a similar view of the spring-carrying frame and spring. Fig. 3 is a detail elevation of the spring-carrying frame and spring looking toward the inner side thereof. Fig. 4 is a horizontal section on the line 4-4, Fig. 1. Fig. 5 is a rear elevation of the hinge.

Similar numerals of reference are employed to indicate corresponding parts in the several views.

The numerals 1 and 2 designate the leaves of the hinge, each of which is provided with two ears 3 and 4, the ear 4 of each leaf being placed just within the ear 3 of the other leaf, the contiguous ears being connected by two pintle-studs 5 on the ears 3 to form two knuckles located at the opposite ends of the hinge and separated by sufficient space for easy operation or movement of the hinge-leaves in a manner common in hinges of this class. The inner opposing edges 6 of the leaves 1 and 2 are beveled or inclined inwardly toward each other, and at their terminals have coinciding stops 7, which limit the backward movement of the leaves, these stops being so positioned that when a door or other closure connected to the hinge is fully closed they will come together and obstruct further movement of the leaves with obvious advantages. The inner edges 6 of the leaves 1 and 2

2 at the center have openings or slots 8 formed therein, one in each, and adjacent to each slot and forming part of the edge of the leaf in which the slot is formed is a coupling rib or 5 enlargement 9, which forms the inner side wall of the slot. The outer edges of these coupling-ribs 9 are rounded, and the inner edges are projected to come into close relation when the hinge-leaves are in alinement, 10 as shown by Figs. 1, 2, and 5. A spring-carrying frame 10 is removably inserted between the inner ears 4 and the respective leaves, the ends or extremities of this frame having loose movement with respect to said ears and 15 unattached thereto. The spring-frame consists of two members 11 and 12, each having inwardly-projecting heads 13 and 14 at opposite ends, the heads 14 being within the heads 13 and formed with central sockets 15 to receive pintle-studs 16, projecting inwardly from the heads 13. The heads 14 are thicker than the heads 13 and have inwardly-extending circular bosses 17, over which are fitted the opposite terminal helices of a coil-spring 18, 20 the opposite ends 19 of this spring being projected in opposite directions and engaging seat enlargements 20 in the opposite edges of the respective members 11 and 12, adjacent to the heads 14. The seat enlargements 25 extend outwardly beyond the heads 14 in reverse position to form guard-lugs 21 for the heads 13, the inner edges of said guard-lugs being concaved to permit the heads 13 to have free movement with relation thereto.

30 One of the most important features of the present invention is the formation of a stop 22 with the rear portion of each head 14, the stops of the respective heads 14 being in reverse position and both stops held in firm engagement with the rear edge portions of the sides of the members 11 and 12 when the spring 17 is inserted in the members. The function of these stops is to restrict the inner or rearward contraction of the two members 40 45 50 55 60 65 70 75 80 85 90 95 100 105 110 115 120 125 130

11 and 12 to control the spaced relation between rearwardly-extending projections, tongues, or claws 23, forming parts of the sides of the said members 11 and 12, there being one projection, tongue, or claw on each member. The projections, tongues, or claws are inclined rearwardly toward each other and have their inner edges constructed with longitudinally-disposed concave seats 24 to fit over and move on the outer rounded edges of the coupling-ribs 9. The minimum distance between the edges of the projections, tongues, or claws 23 is less than the maximum distance between the outer rounded edges of the coupling-ribs 9, and to facilitate the application of the projections, tongues, or claws the rear surfaces of the same are given a convex contour.

In assembling the spring-carrying frame it is positioned between the inner ears 4 and 65 turned at an angle to cause one of the pro-

jections, tongues, or claws 23 to engage one of the openings or slots 8 and is then pressed over until the opposite projection, tongue, or claw passes the remaining coupling-rib 9 and extends into operative relation to the other opening or slot 8. In connecting the projections, tongues, or claws 23 to the coupling-ribs in the manner just explained the said projections, tongues, or claws are expanded against the resistance of the spring 17, and 75 while the tongues or projections have unrestricted movement over the outer rounded edges of the coupling-ribs, owing to the concave seats in the projections or tongues, the latter are held with such restriction in connection with the coupling-ribs that accidental displacement of the spring-carrying frame is prevented during the operation of the hinge.

This improved hinge may be properly termed a "holdback-hinge" when the spring-carrying frame is assembled with the hinge-leaves. Furthermore, when the spring-carrying frame is in connection with the leaves loose separating movement thereof is obstructed; but as soon as the spring-carrying frame is rolled in either direction by lateral pressure exerted thereagainst and disconnected from the coupling-ribs the parts of the hinge may be readily separated. It requires but very little lateral pressure to separate the spring-carrying frame from the hinge-leaves, and in exerting such pressure the maximum tension of the spring does not have to be overcome, owing to the stop arrangement heretofore explained.

The improved hinge is adapted to be applied to screen-doors and other closures where it may be found useful, and in different applications changes in the proportions, dimensions, and minor details may be resorted to without departing from the spirit of the invention.

Having thus fully described the invention, what is claimed as new is—

1. In a hinge, terminally-connected leaves, and a spring-carrying frame having parts engaging the outer portions of the inner edges of the leaves and interposed between the connections for the latter, the said parts of the spring-carrying frame being removable and self-attachable by a transverse rolling movement with respect to the leaves.

2. In a hinge, the combination of connected hinge members, having longitudinal coupling-ribs at the inner edges and openings adjacent to the ribs, a spring-frame having members with longitudinal projections movably and detachably engaging the said ribs and also provided with reversely-arranged stop devices at opposite ends, and a spring disposed in and solely engaging the members of said frame.

3. In a hinge, the combination of movably-connected leaves, and a frame with a spring disposed therein, said frame having movable members with projections engaging portions

of the leaves and reversely-arranged end stops normally bearing on portions of the opposite members of the frame.

4. In a hinge, the combination of connected leaves, and a frame carrying a spring and including movable members having projections engaging opposite parts of the leaves, the projections forming the sole connecting means between the leaves and the frame and attachable and detachable by a transverse rolling movement with respect to the leaves without requiring direct manual pressure on the spring.

5. In a hinge, the combination of movably and separably connected leaves, a frame detachably interposed between the connected portions of the leaves and including two movable members each of which has reversely-arranged end stops and rearwardly-extending projections to engage portions of the leaves, the projections of the members being operative to attach and detach the same by a transverse rolling movement with respect to the leaves and without resorting to direct manual pressure on the spring and a spring interposed between and solely engaging the members of the frame.

6. In a hinge, the combination of movably and separably connected leaves having intermediate coupling-ribs, and a frame carrying a spring having two movable members provided with rearwardly-extending projections to removably and loosely engage the said ribs and attachable and detachable with respect to the latter by a rolling movement transversely of the leaves.

7. In a hinge, the combination of separably-connected leaves, a frame removably interposed between the connected portion of the leaves and including two interfitting members having intermediate projections engaging portions of the leaves, and a spring disposed in and having its terminals solely engaging the said members, the members being provided with reversely-arranged end stops engaging portions of the opposite members to throw the tension of the spring on said members and for restricting the tension of the spring on the projections.

50 8. In a hinge, the combination of leaves

having separably-connected knuckles at opposite extremities, a seat-space being formed between the knuckles and the inner opposing edges of the leaves having intermediate coupling-ribs with outer rounded edges and longitudinal openings adjacent to said ribs, a frame having two members movably assembled and provided with rearwardly-extending longitudinal projections to engage the outer portions of the ribs, the inner opposing edges of the projections being formed with longitudinal concave seats, and a spring disposed in the said frame and having the opposite terminals thereof individually engaging the opposite frame members, the latter having means co-operating with each other to restrict the tension of the spring with relation to the projections.

9. In a hinge, the combination of connected leaves, a frame removably mounted between the connected portions of the leaves and attachable and detachable by a transverse rolling movement with respect to the latter and having movably-assembled companion members with terminal stops in reverse positions normally held in engagement with parts of the opposite sides of the individual members and also with rearwardly-extending projections to engage portions of the leaves, and a spring interposed between the opposite terminals of the frame and having its ends engaging the sides of the members of the frame, the leaves also having rear stop devices adjacent to the ends thereof.

10. A hinge, having two movably and separably connected leaves, and a frame carrying a spring, said frame being removably interposed between the connected portions of the hinge and provided with means to institute a movable wedging attachment with respect to the leaves by application thereto of lateral rolling pressure transversely of the leaves without directly compressing the spring.

In testimony whereof I have hereunto set my hand in presence of two subscribing witnesses.
